UNITED STATES PATENT OFFICE.

PRENTICE E. SKELTON, OF INDIANAPOLIS, INDIANA.

DISHWASHER.

Application filed February 28, 1927. Serial No. 171,561.

This invention relates to dish washing machines and the prime feature of the invention is the arrangement of the dish holding basket in such manner that when water is injected into the basket for washing the dishes, the basket will be caused to rotate from the force of the streams of water.

A further feature of the invention is in so arranging the streams of water that they will thoroughly wash and rinse all the dishes within the basket.

A further feature of the invention is the provision of means for draining off the water from the dishes, in such manner that the dishes will dry without showing streaks or tear paths, after the washing operation has been completed.

A further feature of the invention is in so constructing the various parts of the machine that the several parts may be readily assembled together and form a rigid non-vibrating unit.

A further feature of the invention is the provision of a bearing for the dish receiving basket whereby the friction set up will be reduced to a minimum.

A further feature of the invention is the provision of means for ventilating the interior of the machine during and after the washing operation, whereby the machine will be maintained in a more sanitary condition.

Other objects and advantages will be hereinafter more fully set forth and pointed out in the accompanying specification.

In the accompanying drawings which are made of a part of this application, Figure 1 is a top plan view of the machine; Fig. 2 is a similar view with the top covering broken away; Fig. 3 is a sectional view thru the machine, substantially along the line 3-3, Fig. 2; and Fig. 4 is a similar view substantially along the line 4-4, Fig. 2.

Referring to the drawings, in which similar reference numerals designate corresponding parts thruout the several views, 1 indicates the body of the machine, which is preferably constructed of any suitable sheet metal, and 2 indicates the supporting legs therefor.

Positioned within the body portion 1 is a tank 3, also preferably constructed of suitable sheet metal and supported in any suitable manner, as by means of a cross truss 4, the ends of which are attached to the walls

of the body 1, and a central post 5, the lower end of which engages a cross truss 6, the trusses 4 and 6 preventing lateral vibration of the post. In order to easily and properly assemble the post with the two trusses, it is preferably made in two sections and secured together by means of a coupling 7, and said post is preferably hollow, as shown.

The upper end of the post 5 projects a distance into the tank 3 and receives a hollow sleeve 8, to which is attached a basket 9, the walls of which are preferably constructed of mesh wire 10, so that water may be readily entered thru the wall and onto the dishes 11 stacked therein. The basket 9 is firmly secured to the sleeve 8 by means of collars 12, while the two sections of the post 5 are attached to their respective trusses by means of collars 13 and 14.

Threaded or otherwise secured in the upper end of the post 5 is a cone bearing head 15, the bearing face of which has a channel 16 therein to serve as a lubricant retainer and also to reduce friction. Fitting over the bearing head 15 is a bearing socket 17, which is fixed to the sleeve 8, said socket having a nut 18 formed thereon so that the socket may be readily attached to or released from the sleeve, and the bearing head 15 likewise has a nut 19 formed on its under surface so that a wrench or tool may be readily applied for attaching or releasing the head from the post 5.

The body portion 1 has a covering 20 therefor, which is preferably hinged at one edge so that it may be swung to open position to give ready access to the basket 9, whereby the dishes may be readily introduced into or removed from the basket, and if preferred, a section of glass 21 or other transparent material may be provided at a suitable point in the covering, thus giving a vision of the interior of the basket and tank, during the washing operation.

In order to ventilate the interior of the body 1 during and after the washing operation, a series of openings 22 are formed thru the walls of the body 1, adjacent its upper edge, said openings being so positioned that the water employed for washing the dishes will not come in contact therewith.

The water for washing and rinsing the dishes is carried thru pipes 23 and 24, from a general pipe line 25, a suitable valve 26 being provided for controlling the passage of the water thru the pipes. The pipes 23

and 24 are preferably arranged vertically and on diametrically opposite sides of the basket so that the stream or jets of water from nozzle openings 27 and 28 will strike the basket 9 at a tangent, also the dishes therein, the force of the water serving to rotate the basket 9, thus bringing the water into contact with all the dishes within the basket, and by properly arranging the dishes 10 edgewise within the basket, substantially all the water will drain therefrom by gravity. It will likewise be seen that a certain amount of the water will strike against the walls of the tank 3, and then rebound against the basket 9, the force of which will aid in rotating the basket, as well as aiding in the washing operation. As best shown in Fig. 2 of the drawing, the tank 3 has panels A, which are at an angle to the main walls of 15 the tank, giving a polygonal outline to the tank, so that the water will more readily rebound when thrown against the walls thereof. The streams of water may have various paths of travel depending somewhat upon 20 the manner in which the dishes are stacked within the basket. In some instances, the water will travel substantially in a straight line thru portions of the basket and its contents, as indicated by the arrows B, or the 25 streams may be caused to strike along the walls of the tank 3 at any and various points, as designated by the arrows C. The nozzle openings 27 are preferably at a different altitude from the nozzle openings 28 or 30 in somewhat staggered relation with each other, thus insuring that all the dishes within the basket will be subjected to the force of the water discharged into the basket from the different nozzle openings. By arranging 35 the nozzle openings 27 and 28 in staggered relation, the streams of water, due to the rotation of the basket 9, will be caused to assume a more or less spiral or whirling path and will more thoroughly intermingle and 40 give a more perfect washing operation and will materially aid in imparting rotating movement to the basket.

The water when leaving the basket 9, de-

scends into the tank 3 and is drained therefrom thru a drain 29, which has a valve 30 for opening or closing the drain. The drain 29 discharges the water into the body portion 1, from whence it passes into a sewer thru the regulation drainage 31.

55 Due to the whirling action of the basket 9, and thru centrifugal force set up, the volume of water within the basket will normally assume substantially the position shown by dotted line D, as shown in Fig. 3 of the drawing, thus providing a wall of water, against which the streams of water from the nozzles strike.

In operation, the dishes are first stacked in the basket 9, when the valve 26 is opened 60 and jets of water discharged against and

thru the basket, the force of the water striking said basket, causing it to rotate, whereby the dishes within said basket will be successively brought into the path of the streams of water, and thus thoroughly cleansed of 70 all adhering particles. After a prescribed length of time, the valve 26 is closed and the valve 30 opened to drain the water into the body 1, after which the valve 30 is closed and the valve 26 again opened, thus discharging jets of clean water over and between the dishes for thoroughly rinsing them. A certain amount of water remains on the floor of the tank 3, and also on the floor of the body portion 1, consequently a 80 sufficient amount of moisture is retained around the dishes in the basket to prevent tear paths or streaks forming on the dishes, during the drying operation. This completes the washing operation and by removing the dishes from the basket a new supply of dishes may be placed therein and the washing operation repeated.

The main walls and panels A of the tank 3 being stationary and the basket 9 being 90 revolved, the water between the walls of said tank and basket is led into numerous traveling whirl pools as indicated by E in Fig. 2; and the crest of the water line D is largely composed of such whirl pools.

95 Referring to Fig. 2, the letter F denotes a glancing stream of water such as is caused by one of the spray streams striking a dish 11, shown in Fig. 3. Said stream F being thus directed against the walls of the tank 100 3 and glancing therefrom in the form of stream C which sometimes again strikes one of the panels A and thence against the main walls of said tank, etc.

105 It will be obvious from the foregoing that the invention sets up a combination of friction, centrifugal force and spray actions which cooperate to give a variety of movements against and between the dishes, thus washed.

110 While the description and drawing illustrates in a general way, certain instrumentalities which may be employed in carrying the invention into effect, it is evident that many modifications may be made in the 115 various details, without departing from the scope of the appended claims, it being understood that the invention is not restricted to the particular forms, herein described.

120 What I claim is:

1. In dish washing machine, a revolvably mounted basket, said basket having perforated walls; vertical water conveying pipes adjacent the outer walls of said basket; said pipes having nozzle openings therein, the 125 nozzle openings in one pipe being at different altitudes or in staggered relation with the nozzle openings of the other pipe, said nozzle openings being positioned for causing streams of water therefrom to strike 130

the walls of said basket in a manner to set up rotation of the basket; and means for controlling the water passing thru said pipes.

5 2. In a dish washing machine, a stationary tank having substantially polygonally arranged side walls to provide flat surfaces at different angles against which water may strike and rebound; a basket revolvably mounted within said tank, said basket having perforate walls; means for directing streams of water against said basket for causing said basket to rotate and for cleansing the contents of the basket; means for controlling the admission of the water to the basket; and means for draining the water from the tank.

3. In a dish washing machine, a hollow body, a closure therefor adapted to retain steam and odors in the body during the washing operation and for preventing the escape of splashing water, a basket within said body portion adapted to receive dishes to be washed, a hollow sleeve to which said basket is attached, a post fixed within said body over which said sleeve fits, a conical bearing head at the upper end of said post, a bearing socket fixed to said sleeve and fitting over and bearing against said head, said head having a channel for reducing frictional surface and providing a lubricant reservoir, and means for directing streams of water against said basket at different

altitudes for cleansing the contents of the basket and setting up rotation thereof. 35

4. In a dish washing machine, a hollow body portion, having vent openings adjacent its upper end; a closure for the body to prevent the escape of steam and odors; a tank fixed within said body portion; a perforate basket mounted within said tank; a bearing for said basket; means for directing streams of water against said basket at different altitudes and in a manner to cleanse the contents of the basket and cause said 45 basket to rotate; means for controlling the streams of water; and means for draining the water from said tank and body portion.

5. In a dish washing machine, a hollow post formed in sections; means for removably connecting said sections together; a hollow sleeve fitting around a portion of said post; means for anchoring and supporting said post; a conical bearing head, 55 at the upper end of said post; means on the head for receiving a tool for attaching or releasing said head; a bearing socket attached to said sleeve; means on the socket for receiving a tool for attaching or releasing the socket; and a perforate basket carried by said sleeve and rotatable therewith.

In testimony whereof, I have hereunto set my hand on this the 21st day of February, 1927, A. D.

PRENTICE E. SKELTON.
